UNITED STATES PATENT OFFICE.

ISRAEL C. HALL, OF SANBORNTON BRIDGE, NEW HAMPSHIRE.

IMPROVEMENT IN WHIFFLETREES.

Specification forming part of Letters Patent No. **92,963**, dated July 27, 1869.

To all persons to whom these presents may come:

Be it known that I, ISRAEL C. HALL, of Sanbornton Bridge, of the county of Belknap and State of New Hampshire, have made a new and useful invention, having reference to the Whiffletree of a Carriage; and I do hereby declare the same to be fully described in the following specification, and represented in the accompanying drawings, of which—

Figure 1 is a top view, Fig. 2 a side elevation, and Fig. 3 a longitudinal section, of it and the end portion of a whiffletree of a carriage.

The invention may be termed a new and useful or improved "whiffletree-snap," its purpose being to hold a harness-trace securely on the head of the whiffletree.

In the drawings, A denotes part of a whiffletree as provided with a buttoning-head, B, of the common kind. To the whiffletree a spring, C, carrying a hooked projection, a, is affixed by screws b b, arranged at or near the rear end of the spring. The projection a enters the eye c of the head B. A lever, D, is pivoted to the spring and passes through it, the shorter arm of such lever being made to rest against the whiffletree or a piece of metal, d, sunk therein and projected back from the ferrule e, which encompasses the whiffletree at its end. The

longer arm of the lever extends down along the hook, in manner as represented.

By taking hold of the said arm the lever may be moved so as to cause the hook to be withdrawn from the eye of the trace-head.

While a trace may be hitched on the said head it will be held thereon by the snap; but by moving the hook of the snap out of the eye of the hitching-head, and sufficiently away therefrom, the trace can be unhitched from the said head.

From the above it will be seen that my said whiffletree-snap not only can be easily operated, but, in practice, will serve to excellent advantage in securing a trace to the whiffletree, or preventing such trace from becoming disconnected therefrom while the carriage to which it may belong may be in use or movement.

I claim—

The arrangement and combination of the spring C, the hook a, and the lever D with the whiffletree A and its hitching-head B, as set forth.

ISRAEL C. HALL.
